(57) **CLAIM**

The ornamental design for a foldable toothbrush, as shown and described.

DESCRIPTION

FIG. 1 is a bottom front perspective view of a foldable toothbrush in an extended configuration, showing my design;

FIG. 2 is a top rear perspective view thereof;

FIG. 3 is a left side elevation view thereof;

FIG. 4 is a right side elevation view thereof;

FIG. 5 is a front elevation view thereof;

FIG. 6 is a rear elevation view thereof;

FIG. 7 is a top plan view thereof;

FIG. 8 is a bottom plan view thereof;

FIG. 9 is a left side elevation view of the design shown in FIGS. 1-8 thereof, but in a folded configuration;

FIG. 10 is a right side elevation view thereof;

FIG. 11 is a front elevation view thereof;

FIG. 12 is a rear elevation view thereof;

FIG. 13 is a top plan view thereof; and,

FIG. 14 is a bottom plan view thereof.

The broken lines shown in the drawings illustrate features of the article that form no part of the claim.
